UNITED STATES PATENT OFFICE.

WILLIAM PARKIN, OF TAUNTON, MASSACHUSETTS, ASSIGNOR TO REED & BARTON, OF SAME PLACE.

DESIGN FOR A CAKE-TAZZA OR FLOWER-STAND.

Specification forming part of Design No. 5,445, dated December 19, 1871.

To all persons to whom these presents may come:

Be it known that I, WILLIAM PARKIN, of Taunton, of the county of Bristol and State of Massachusetts, have invented or produced a new ornamental Design for a Cake-Tazza or Flower-Stand; and do hereby declare the same to be described as follows and represented in the accompanying drawing, which is an elevation of the tazza:

The tazza is composed of the bowl A and the stand B. The bowl, in the general form of its bottom, is a paraboloid, *a*, terminating at top in a short cylinder, *b*, and at bottom in a semi-elliptical dish, *c*, which is imposed on three heads, *d*, having busts provided with wings *e e*. Each

of the heads crowns a curved leg, *f*, terminating in a leaved voluted foot, *g*, imposed on a rectangular base, *h*. These bases rest on a curved conical bottom, *i*, springing from a short milled cylinder, *k*. The several legs of the stand encompass a central column, *l*, provided with connection-disks *m n*. The forms of the several parts above mentioned are as shown by the drawing.

I claim—

The design of the stand and that of the bowl, also that of each leg of the stand.

WILLIAM PARKIN.
